CLAIM

The ornamental design for a footwear as shown and described.

DESCRIPTION

FIG. 1 is a front, top, and left side perspective view of an embodiment of a footwear according to the new design; FIG. 2 is a front side elevation view thereof; FIG. 3 is a back side elevation view thereof; FIG. 4 is a left side elevation view thereof; FIG. 5 is a right side elevation view thereof; FIG. 6 is a top plan view thereof; and, FIG. 7 is a back, bottom, and right side perspective thereof. The broken lines in the drawings show portions that form no part of the claimed design.
